UNITED STATES PATENT OFFICE.

FREDERICK W. MENNICKHEIM, JR., OF SUSSEX, NEW JERSEY, ASSIGNOR OF ONE-HALF TO MICHAEL J. WALSH, OF SUSSEX, NEW JERSEY.

SPIGOT.

1,107,435.

Specification of Letters Patent. Patented Aug. 18, 1914.

Application filed March 21, 1914. Serial No. 826,326.

To all whom it may concern:

Be it known that I, FREDERICK W. MENNICKHEIM, Jr., a citizen of the United States, residing at Sussex, in the county of Sussex 5 and State of New Jersey, have invented certain new and useful Improvements in Spigots, of which the following is a specification, reference being had to the accompanying drawings.

10 This invention relates to spigots, and more particularly to that class of spigots which are used in connection with water tanks for watering animals.

An object of this invention is the provision 15 of a spigot of this class, the spigot comprising a body having a pair of bores extending therethrough, one of the bores being adapted to communicate with a suitable pipe through which the water flows to the watering fountain, the other bore being adapted for use in 20 draining the tank, and is normally closed.

Another object of this invention is the provision of a spigot having a pair of bores extending therethrough, the spigot comprising 25 a body which is molded or cast in one piece of material.

With these and other objects in view, my invention relates to the novel construction, to be hereinafter more fully described, 30 claimed and illustrated in the accompanying drawings, in which—

Figure 1 is a longitudinal sectional view of the spigot. Fig. 2 is a section on the line 2—2 of Fig. 1. Fig. 3 is a section on the line 35 3—3 of Fig. 1.

Referring more particularly to the drawing, the spigot consists of a body 5 having a bore 6 extending longitudinally therethrough. The body 5 is preferably tubular 40 in form, and is provided at its inner end with a reduced portion 7, and also formed at its outer end with a reduced portion 8, the reduced portions of the body being exteriorly threaded. The body is formed on one side 45 thereof with an enlarged portion 9, the opposite ends of the enlarged portion of the body extending to the threads and the reduced ends of the main portion of the body. The periphery of the enlarged portion at its 50 inner end is curved to form a continuation of the curvature of the periphery of the main portion of the body, so that in cross section the body is annular at its inner end as illustrated in Fig. 2 of the drawing, and is exteriorly threaded as at 10 for engagement in

a threaded opening in the water tank 11. The enlarged portion 9 of the body is formed with a longitudinal bore 12, the inner end of the bore extending in parallel relation with the bore 6 of the main portion 60 of the body, and the outer end of the bore 12 being off-set as at 13, the outer extremity of the bore being threaded as at 14 for connection with a threaded plug 15, which is adapted to close the bore 12. 65

In the practical use of my invention, the spigot is connected in a threaded opening in the bottom of the tank 11 by the threaded portion 10 of the spigot, the spigot being screwed into the opening of the tank 22 70 until the upper extremity of the enlarged portion of the body is disposed flush with the upper face of the bottom of the tank. A valve (not shown) which may be of any desired construction, may be threaded upon 75 the reduced portion 7 which projects upwardly into the tank proper, and a pipe (not shown) is adapted for threaded engagement with the reduced portion 8 of the body, the pipe being adapted to feed the 80 water in the tank to a suitable drinking fountain (not shown). When it is desired to clean the interior of the tank, the plug 15 may be removed from the outer end of the bore 12, and as the upper end of the 85 bore 12 is disposed flush with the inner wall and the body of the tank, it will be seen that all of the water contained within the tank may be drained therefrom. The bottom of the tank may then be cleaned and 90 any sediment disposed thereupon may be discharged from the tank through the bore 12 whereupon the plug 15 may be again engaged in the bore 12 and the tank filled with water so that the same may be fed to 95 the drinking fountain.

Having thus fully described my invention, what I claim as new and desire to secure by Letters Patent is:

1. A spigot comprising a tubular body, 100 the opposite ends of said body being reduced and exteriorly threaded, said body having an enlarged portion formed on one side thereof between said reduced portions, said enlarged portion having a bore extending 105 therethrough, means for closing said bore, and means for mounting the spigot in a suitable support, as and for the purpose described.

2. A device of the character described 110

comprising a body having a bore extending longitudinally therethrough, said body being enlarged on one side thereof, the enlarged side of said body having a bore extending therethrough, means for closing the last mentioned bore, the body and the enlarged portion thereof at the inner end of the body being annular in cross-section and

threaded, said body having a reduced longitudinal extension at its inner end. 10

In testimony whereof I hereunto affix my signature in the presence of two witnesses.

FREDERICK W. MENNICKHEIM, JR.
